FASTENER FEEDING AND DRIVING MECHANISM

Edgar S. Moore, Oswald Stuart Neill, and Roy W. Emery, Toronto, Ontario, Canada, assignors to Taymouth Industries Limited, Toronto, Ontario, Canada

Application June 23, 1954, Serial No. 438,724

18 Claims. (Cl. 144—32)

This invention relates to a device for serving fastener elements to a desired position to be operated on by a driving tool.

One of the objects of the invention is to provide means for feeding fasteners to the driving tool and actuating the driving tool wholly by means of fluid pressure.

A further object is to provide simple and effective means for feeding fasteners one at a time to a driving tool.

These objects are attained by means of a fastener feeding mechanism having a passage for carrying fasteners from a fastener container to a driving tool, means for introducing fasteners from the fastener container into said passage, means of said passage for feeding the fasteners one at a time to the tool, and means for operating the fastener introducing means and the fastener feeding means in synchronism, characterised by the provision of a fluid pressure circuit having a connection to the driving tool for actuating said tool, a connection to the said operating means for actuating the said operating means, a connection to the fastener passage for chasing the fasteners in said passage to the tool, a master control valve for controlling fluid pressure in the connection to the operating means, and a supply control valve in the connection to the fastener passage actuated in synchronism with the operating means.

These objects are further attained by the provision of fastener feeding means including a shuttle comprising a reciprocatable plate disposed across the feed passage and dividing the passage into a first part communicating with the fastener container and a second part communicating with the tool, the plate being arranged to receive from the first part of the passage a fastener lying on its side, the plate having a slot through which a fastener may pass and which is adapted to be brought into registration with each of the parts of the passage, the plate being movable from fastener receiving position to another position at which the slot is in register with the second part of the passage to permit a previously received fastener to pass through the slot and discharge into the second part of the passage, and means being provided to reciprocate the plate between the fastener receiving position and the said discharging position to feed the fasteners one at a time to the tool.

The invention is hereafter more particularly described and is illustrated in the annexed drawings in which:

Figure 1 is a top perspective view partly broken away of a fastener server constructed in accordance with the invention;

Figure 2 is a side view also partly broken away of the server taken from the opposite side to Figure 1;

Figure 3 is a side elevation on an enlarged scale of the fastener feeding shuttle broken away in several places to show the operation thereof;

Figure 4 is a diagrammatic perspective view of the shuttle operating mechanism;

Figure 5 is a side elevation partly in section of the driving tool;

2

Figure 6 is a fragmentary view similar to Figure 4 showing the driving tool in fastener driving position; and

Figure 7 is a diagram of the apparatus showing the air circuit.

In the drawings corresponding numerals refer to corresponding parts in the different figures.

This invention is described for use in connection with screws, although it should be understood that it is applicable to various types of fasteners, such as nails, rivets and pins. The fasteners are contained in a storage hopper 1 from which they are fed beneath an adjustable baffle 2 into a feed hopper 3 having a bottom which slopes downwardly and inwardly towards a slot. An elevator 4 reciprocates between upright channel members 6, 6 on upright channel member 5.

The elevator 4 is formed of two plates spaced apart to provide a fastener receiving slot 7 in its upper edge. The upper edge of the elevator slopes downwardly from the back to the front of the hopper. When the elevator 20 is at its lowest position as shown in dotted lines in Figure 2 its upper edge at the back of the hopper will be at or slightly below the bottom of the feed hopper 3 and it will slope down towards the front of the hopper at which point it will be considerably below the bottom of the hopper so that fasteners will cover the fastener receiving slot 7. When the elevator rises some of the fasteners will be caught in the slot 7 with their heads engaging the upper edge of the elevator and their shanks depending in the slot substantially vertically.

In the upper position of the elevator 4 its upper edge is in alignment with the upper edge of a trackway 8 formed of spaced apart plates having a fastener receiving slot 9 therebetween. When the elevator is in its uppermost position fasteners in the fastener receiving slot 7 will be introduced into the slot 9 of the trackway 8 and will slide down said trackway to the shuttle mechanism which will hereafter be described.

The elevator 4 is caused to reciprocate by means of compressed air or other suitable fluid actuating a double-acting piston in a cylinder 10 (see Figure 2). The piston rod 10a is connected to an L-shaped bar 11 which passes through a slot in the channel member 5 and is secured at its upper end to the lower part of the elevator 4 which is shown in its elevated position in Figures 1 45 and 2 and in its lower position in dotted lines in Figure 2.

The lowermost fastener of a procession of fasteners which have passed down the trackway 8 is stopped by a reciprocating shuttle plate 13 having a substantially T-shaped slot 13a extending through it. The plate 13 is reciprocatable by means hereafter described to move the slot 13a into register with the lower end of the fastener receiving slot 9 of the trackway 8 permitting the fastener to be deposited in the slot 13a on its side.

The reciprocating plate 13 slides between plates 12 and 14. Plate 14 has a longitudinal groove 14a therein which receives a complementary rib 13b in the reciprocating plate 13. This provides a guideway for the reciprocating plate 13 on the fixed plate 14 and also provides a groove to accommodate the head of the screw when the screw is lying on its side in the slot 13a with its head at the junction of the T.

Extending through the fixed plate 14 is a slot 14b which opens through opening 15a into screw delivery pipe 15 secured to the underside of the fixed plate 14.

When the reciprocating plate 13 is moved to a position where the slot 13a is in register with the slot 14b the fastener which has been received in the slot 13a drops into the fastener feed pipe 15 through opening 15a from which it passes to a tube 16 and thence to the driving tool hereafter described.

Reciprocation of the shuttle plate 13 is effected by the following means.

Secured to the piston rod 10^a is a substantially Z-shaped rod 17 which is forked at 17^a to receive a longitudinally curved arm 18 secured to a rock shaft 19 rockably mounted on bearing 20 on the upright channel member 5. Secured to the other end of the shaft 19 is a resilient shuttle engaging rock arm 21. Vertical reciprocating movement of the piston rod 11 will be translated into rocking movement of the curved arm 18 which will in turn rock the shaft 19 and the arm 21.

Secured to the underside of the reciprocating shuttle plate 13 at one end thereof is an operating arm 22 extending transversely of the said reciprocating plate terminating in a forked end 22^a which receives the upper end of the rock arm 21. As the arm 21 rocks back and forth, it will move the reciprocating plate 13 back and forth. The operating arm 22 will engage the fixed plate 14 as the reciprocating plate 13 moves to the left, thus acting as a stop to stop the plate 13 with the slot 13^a in register with the slot 14^a. Secured to the underside of the reciprocating plate 13 at the other end is a stop 23 which engages the fixed under plate 14 when the reciprocating plate 13 has been moved to its extreme right hand position, stopping the plate 13 with the slot 13^a in register with the lower end of the fastener receiving slot 9.

To guide the fasteners in the trackway 8 a removable guide bar 24 is mounted above and spaced from the upper edge of the trackway 8 sufficiently to accommodate the head of the fasteners which are travelling in the slot 9. This guide bar is pivoted at its lower end on the fixed plate 14 as shown in Figures 1, 2 and 3, and is removably supported above the trackway by a U-shaped bracket 25 of resilient metal, having holes in the ends of its arms adapted to receive pins 25^a on the sides of the trackway and thus retain the guide bar 24 in readily removable position relative to the trackway, whereby it can be removed to inspect the procession of fasteners travelling down the trackway and to clear the track or straighten the fasteners if any of them should become stuck out of position.

To avoid jamming of fasteners at the entrance to the trackway 8 an ejector 26 is provided hingedly mounted on the upper end of the guide bar 24. This ejector forms a continuation of the upper surface of the guide bar 24 and its front face 26^a is located in an opening 3^a in the front of the feed hopper 3.

A spring 26^b engages the upper surface of the ejector 26 and resiliently retains it in normal position, permitting, however, the ejector to be raised in the event that the elevator should lift some misaligned fasteners and jam them beneath the front face 26^a of the ejector. The spring pressure thus applied to maladjusted fasteners will straighten them or return them to the hopper, thus preventing jamming at the junction between the elevator and the trackway.

The fasteners from the feed pipe 15 are forced through resilient tube 16 to the driving tool illustrated in Figures 5 and 6 of the drawings by means of air pressure carried to the feed pipe 15 through air pipe 27 as shown in Figures 1 and 2. The feed pipe 15 and resilient tube 16 with the trackway provide a passage from the fastener container to the driving tool. The shuttle forms part of the passage for feeding the fasteners one at a time from the trackway to the feed pipe. The fastener driving tool may be of any suitable type of pneumatic screwdriver, 28. Details of the screwdriver are therefore not shown in the drawings except so far as may be necessary to describe the present invention. The screwdriver is operated by compressed air delivered through resilient tube 29 and controlled by means of tool control valve having a convenient manually operable operating lever 30.

Attached to the end of the driver 28 is a serving head which comprises a tubular Y-shaped member having one

branch 31 slidably mounted within a sleeve 32 surrounding the shank 33 of the tool. The other branch 34 extends through a slot 32^a in the sleeve 32 to permit relative movement of the sleeve and the Y-shaped member.

The branch 34 has connected thereto the end of the flexible fastener feeding tube 16. Encircling the shank 33 is a coil spring 35 seated at one end in a counterbore 36 in a reduced tubular extension 37 of the sleeve 32 fitting into the body of the tool.

The opposite end of the spring 35 bears against a guide sleeve mounted within the branch 31 of the tubular Y-shaped member. This spring 35 acts to urge the Y branch 31 out of the sleeve 32 to clear the entrance of the branch 34 into the branch 31 below the tool bit 38 to allow entrance of the screw or fastener into a collet 39 at the lower or outer end of the Y-shaped member.

This collet 39 comprises a plurality of collet or chuck members pivotally mounted on the end of the sleeve 31 and resiliently pressed together by an oil proof elastic band 40 passing around the collets permitting them to open and close to allow the passage of a screw or fastener therethrough, as illustrated in Figures 5 and 6.

The branch 31 is provided with a number of projections 41 (one of which is shown in Figures 5 and 6), which extend through slots in the collet members 39 and guide them in their opening and closing movements and prevent their rotation under driving of the screw. The encircling band 40 acts to close the collet members to the position of Figure 5 with sufficient force to prevent the head of the fastener from passing between the collet members under pressure of air in the tube 16.

Under pressure applied by the operator on the screwdriver, however, to advance the tool bit 38 and shank 33 through the Y-shaped member, the bit will first contact the positioned screw and press it against the work. By pressing the operating lever 30 of tool control valve air is admitted to the screwdriver which causes the bit to rotate and drive the screw into the work.

To prevent the collet from touching or marking a surface into which the screw is to be driven and to transfer the thrust back to the Y in a guided push, a foot 44 is preferably secured to the branch 34 of the Y and this foot projects in advance of the collet. This arrangement prevents an unbalanced thrust in the collet which would, without care, cause one collet member to be displaced differently from another, allowing the screw to tilt.

A set screw 45 is screwed into the Y 31 and projects outwardly through a slot 32^b in the said sleeve 32 opposite to slot 32^a. As the screwdriver is operated the set screw 46 moves from one end to the other of the slot 32^b acting as a stop defining the limits of movement of the Y-shaped member and preventing the spring 35 from ejecting the Y-shaped member.

The device is operated by means of a fluid pressure system, preferably pneumatic and will be so described. Briefly the air system consists of a circuit connected to a suitable source of compressed air having a connection running to the driving tool 28 for actuating said tool, another connection to the elevator-operating cylinder 10, and another connection to fastener feed passage for chasing fasteners to the tool. A master control valve is located in the connection to the operating cylinder 10. This master control valve is actuated through a fluid pressure line controlled by a valve adjacent the tool. A supply control valve in the connection to the fastener feed passage is operated in synchronism with the elevator-operating cylinder to feed a fastener to the tool each time a fastener is introduced into the fastener feed passage. The air under pressure is brought from a suitable source of supply through air supply pipe 46 illustrated in Figure 2 and shown diagrammatically in Figure 6, to a T-joint 47 to which is connected a pipe 48 running to a master control valve 49, also shown in Figure 2 and diagrammatically in Figure 7. In the valve position shown in Figure 7 air pressure will pass from the master valve 49 through

pipe 50 to the underside of cylinder 10, forcing piston 51 to its uppermost position, as shown in Figure 7. In the position shown in Figure 7, air in the upper part of the cylinder 10 has been exhausted through pipe 52, master valve 49 and exhaust 53.

This raises the elevator 4 to the position shown in Figure 1 which is the normal position when the tool is not in use but is ready to be operated.

When the tool is put in use the operating lever 30 of tool control valve 30 is depressed by the operator causing the bit 38 to rotate and the operator then applies pressure to the tool to move the bit forward into driving engagement with the fastener as illustrated in Figure 6. The lever 30 may be depressed simultaneously with supply control lever 54. As shown in Figures 5 and 7, these control members are arranged adjacent to each other, whereby compressing feed control lever 54 will cause it to engage tool lever 30 and thus actuate the screwdriver while at the same time actuating the feeding mechanism. If desired, however, the user may conveniently manipulate them independently. It will be observed by reference to Figure 5 that if the feed control lever 54 should be actuated to feed a fastener through tube 16 while the bit is in its driving position, the fastener is prevented from being fed into the collet by reason of the fact that the shank 33 of the bit 38 blocks the entrance of the Y-branch 34 into the Y-branch 31.

Depression of the supply control lever 54 actuates the master valve 49 to cause the piston 51 in air cylinder 10 to move to its "down" position and to cause the elevator 4 to drop. As it descends, elevator 4 strikes pivoted actuating arm 55 of supply control valve 56 to open said valve and permit passage of air through air pipe 27 to screw delivery pipe 15 to chase a screw down said pipe and through tube 16 to the serving head.

The supply control lever 54 is pivotally mounted on a block 57 (see Figures 5 and 6). The main air pressure supply pipe 29 to the screwdriver 28 passes through the block 57 by means of a passageway 58. There is a by-pass 59 to an air tube 60 which leads to the master valve 49 for operating it.

The by-pass 59 is normally closed by spring pressed ball 61, but spring pressed ball 61 may be pressed by means of plunger 62 out of its seat-engaging position to open by-pass 59 to permit tool-operating air from air supply pipe 27 to pass to the air tube 60.

When the supply control lever 54 is released a spring 63 presses the ball 61 upward into feed engaging position and closes by-pass 59. At the same time the plunger 62 will be forced upwardly and in turn it will raise the lever 54. Connected to the air tube 60 is a passageway 60^a which leads to atmosphere. When the plunger 62 is in lower position it blocks the passageway 60^a. When it is in upper position it permits air from the air tube 60 to pass through the passageway 60^a to atmosphere thus venting the end of the master cylinder 49 and permitting the piston 64 of said master cylinder to return to the normal position shown in Figure 7.

However, when by operation of the supply control lever 54 the piston 64 is moved from the position shown in Figure 7 to the other end of the master control valve 49 air from the pipe 48 will pass into the master valve 49 and thence to the pipe 52 and into the upper end of the actuating cylinder 10 to force the piston 51 down. The air in the cylinder 10 will be exhausted through pipe 50 and the exhaust 65.

When the elevator 4 drops in the hopper, to pick up another screw, simultaneously the reciprocating shuttle plate 13 will be reciprocated through the medium of the rock arm 21 and associated mechanism as already described, carrying a fastener from the bottom of the trackway 8 and depositing it in the fastener feed pipe 15. As the actuating piston 51 reaches the bottom of its stroke, the elevator 4 will approach its lowermost position and

will engage the actuating arm 55 of the supply control valve 56. This supply control valve may be of any suitable construction but is shown diagrammatically in Figure 7 as provided with a piston 66 which is spring pressed by spring 67 against the actuating arm 55 to normally close the air pipe 27. When the actuating arm 55 is pressed back by the downcoming elevator 4, the piston 66 is moved to open to the passage and permit air under pressure to enter the fastener feed pipe 15 and chase a screw down the tube 16 to the tool 28, where, if the screwdriver is in operation, it will be stopped by the shank of the bit until the screwing operation is completed and the tool is released to permit the bit to retract and admit the screw through the Y-branch 34 into the Y-branch 31 where it will be held by the collet 39.

As soon as the feed control lever 54 is released, the unbalance of pressure in the cylinder 49 will permit the piston 64 to return to initial position, causing the piston 51 in air cylinder 10 to reverse its position, lift the elevator 4, and release the arm 55 to close the air supply to the fastener feed pipe. The machine is then prepared to deliver the next fastener.

It will be observed by reference particularly to Figures 1, 2 and 3 that when the reciprocating shuttle plate 13 is retracted, it will close the openings 14^a and 15^a into the fastener feed pipe 15, preventing escape of the air under pressure used to chase the fastener down the feed pipe 15 and the tube 16.

What we claim as our invention is:

1. A fastener feeding and driving mechanism having a driving tool, a passage for carrying fasteners from a fastener container to the driving tool, means for introducing fasteners from the fastener container into said passage, means associated with said passage for feeding the fasteners one at a time to the tool, and means for operating the fastener introducing means and the fastener feeding means in synchronism, characterised by the provision of a fluid pressure circuit having a connection to the driving tool for actuating said tool, a connection to the said operating means for actuating the said operating means, a connection to the fastener passage for chasing the fasteners in said passage to the tool, a master control valve for controlling fluid pressure in the connection to the operating means, and a supply control valve in the connection to the fastener passage actuated in synchronism with the operating means.

2. A faster feeding and driving mechanism having a driving tool, a passage for carrying fasteners from a fastener container to the driving tool, means for introducing fasteners from the fastener container into said passage, means associated with said passage for feeding the fasteners one at a time to the tool, and means for operating the fastener introducing means and the fastener feeding means in synchronism, characterised by the provision of a fluid pressure circuit having a connection to the driving tool for actuating said tool, a connection to the said operating means for actuating the said operating means, a connection to the fastener passage for chasing the fasteners in said passage to the tool, a master control valve for controlling fluid pressure in the connection to the operating means, a fluid pressure line in said circuit for actuating the master control valve, a pressure controlling valve located in said line adjacent the driving tool, and a supply control valve in the connection to the fastener passage actuated in synchronism with the operating means.

3. A fastener feeding and driving mechanism having a driving tool, a passage for carrying fasteners from a fastener container to the driving tool, means for introducing fasteners from the fastener container into said passage, means associated with said passage for feeding the fasteners one at a time to the tool, and means for operating the fastener introducing means and the fastener feeding means in synchronism, characterised by the provision of a fluid pressure circuit having a connection to the driving tool for actuating said tool, a connection to the said operating

means for actuating the said operating means, a connection to the fastener passage for chasing the fasteners in said passage to the tool, a master control valve for controlling fluid pressure in the connection to the operating means, a fluid pressure line in said circuit for actuating the master control valve, a pressure controlling valve located in said line and having a manually operable control member located adjacent the driving tool, and a valve in the fluid pressure connection to the tool having a manually operable control member located adjacent the first mentioned valve control member whereby the user may conveniently manipulate both said control members.

4. Mechanism as claimed in claim 3 in which the valve in the fluid pressure line to the master valve includes a valve closing member, a plunger for operating said valve to open and close the line, and a passage to open the pressure line to atmosphere when the valve is closed.

5. A fastener feeding and driving mechanism having a passage for carrying fasteners from a fastener container to a driving tool, means for introducing fasteners from the fastener container into the passage, means for operating the fastener introducing means and the fastener feeding means, and means associated with said passage for feeding the fasteners one at a time to the tool, characterised in that the fastener feeding means includes a shuttle comprising a reciprocatable plate disposed across the feed passage and dividing the passage into a first part communicating with the fastener container and a second part communicating with the tool, the plate being arranged to receive from the first part of the passage a fastener lying on its side, the plate having a slot through which a fastener may pass and which is adapted to be brought into registration with each of the parts of the passage, the plate being movable from fastener receiving position to another position at which the slot is in register with the second part of the passage to permit a previously received fastener to pass through the slot and discharge into the second part of the passage, and means to reciprocate the plate between the fastener receiving position and the said discharging position to feed the fasteners one at a time to the tool.

6. Mechanism as claimed in claim 5 in which the reciprocatable plate is slidable between upper and lower fixed plates, the upper plate having an opening therethrough communicating with the first part of the passage and registering with the slot in the reciprocatable plate in one position of said plate and the lower plate having an opening therethrough and communicating with the second part of the passage.

7. Mechanism as claimed in claim 5 in which the first part of the passage is offset from the second part whereby fasteners are received in the slot in the reciprocatable plate from the first part of the passage and carried to and deposited in the second part of the passage.

8. Mechanism as claimed in claim 5 including a fluid pressure circuit having a fluid pressure connection to the fastener passage immediately below the shuttle for chasing the fasteners to the tool.

9. A fastener feeding and driving mechanism having a passage for carrying fasteners from a fastener container to a driving tool, means for introducing fasteners from the fastener container into the passage, means for operating the fastener introducing means and the fastener feeding means, and means associated with said passage for feeding the fasteners one at a time to the tool, characterised in that the fastener feeding means includes a shuttle comprising a reciprocatable plate disposed across the feed passage and dividing the passage into a first part communicating with the fastener container and a second part communicating with the tool, the plate being arranged to receive from the first part of the passage a fastener lying on its side, the plate having a slot through which a fastener may pass and which is adapted to be brought into registration with each of the parts of the passage, the plate being movable from fastener receiv-

ing position to another position at which the slot is in register with the second part of the passage to permit a previously received fastener to pass through the slot and discharge into the second part of the passage, means to reciprocate the plate between the fastener receiving position and the said discharging position to feed the fasteners one at a time to the tool, a fluid pressure circuit having a fluid pressure connection to the fastener passage immediately below the shuttle for chasing the fasteners to the tool, and a supply control valve in the fluid pressure connection to the fastener passage actuated in synchronism with the shuttle to permit fluid pressure to pass through the connection to the fastener passage after the shuttle has deposited a fastener therein below the shuttle.

10. Mechanism as claimed in claim 9 in which the reciprocatable plate closes the fastener passage above the fastener after depositing the fastener therein.

11. Mechanism as claimed in claim 9 in which the supply control valve is mechanically actuated by the means for operating the fastener feeding means.

12. Mechanism as claimed in claim 5 in which the means for operating the fastener feeding means includes a reciprocating member which reciprocates the shuttle.

13. A mechanism as claimed in claim 5 in which the means for reciprocating the fastener feeding plate includes an arm having an opening therein, a curved arm fixed on a rock shaft and extending through the opening in said arm, and a shuttle engaging rock arm fixed to said rock shaft whereby reciprocation of the reciprocating member rocks the curved arm, the rock shaft and the rock arm to reciprocate the shuttle.

14. Fastener feeding and driving mechanism including a driving tool and a fastener container having an inclined trackway having a slot therein for carrying fasteners from the fastener container to the driving tool, an elevator in the fastener container having an inclined slot therein for receiving fasteners, means for vertically reciprocating the elevator from a position adjacent the bottom of the hopper to a position in alignment with the trackway, characterised in that an ejector is resiliently mounted above the trackway substantially at the junction between the trackway and the fastener receiving slot when the elevator is in elevated position, said ejector being adapted to give way under pressure of misaligned fasteners and return to normal position as the elevator descends to reject or align misaligned fasteners.

15. Fastener feeding and driving mechanism as claimed in claim 14 characterised in that the groove in the inclined trackway is formed of spaced rails adapted to receive the shank of a headed fastener between them with the head of the fastener resting on the upper edge of the rails and the ejector consists of a resiliently mounted extension of a bar which overlies the rails and is spaced from them to accommodate the heads of the fasteners.

16. Fastener feeding and driving mechanism having a driving tool, a passage for carrying fasteners from a fastener container to the driving tool, means for introducing fasteners from the fastener container into said passage, means associated with said passage for feeding the fasteners one at a time to the tool, and means for operating the fastener introducing means and the fastener feeding means in synchronism, characterised in that the fastener passage which extends from the fastener container to the means for feeding the fasteners one at a time to the tool comprises an inclined trackway having spaced rails adapted to receive the shank of a headed fastener therebetween with the head resting on the upper edges of the rails, a bar overlying the rails and removably supported thereby, and a support for the bar comprising spring clips.

17. A fastener feeding and driving mechanism having a driving tool, a passage for carrying fasteners from a fastener container to the driving tool, means for introducing fasteners from the fastener container into said passage, means associated with said passage for feeding

the fasteners one at a time to the tool, and means for operating the fastener introducing means and the fastener feeding means in synchronism, characterised in that the fastener container comprises two parts one of which opens into the fastener passage and is separated from the other part by a baffle to limit the number of fasteners passing from said other part to the part which opens into the fastener passage to prevent fastener accumulations adjacent the entrance to said fastener passage.

18. A fastener feeding and driving mechanism having 10 a driving tool, means for actuating the driving tool, a passage for carrying fasteners from a fastener container to the driving tool, means for introducing fasteners from the fastener container into said passage, means associated with said passage for feeding the fasteners one at a time 15 to the tool, and means for operating the fastener introducing means and the fastener feeding means in synchronism, characterised by the provision of a fluid pressure circuit having a connection to the said operating means for actuating the said operating means, a connection to 20

5

the fastener passage for chasing the fasteners in said passage to the tool, a master control valve for controlling fluid pressure in the connection to the operating means, and a supply control valve in the connection to the fastener passage actuated in synchronism with the operating means.
